ELECTRICAL SWITCH WITH THE OUTER CONDUCTORS OF COAXIAL LEADS CONNECTED TO SPACED SHIELD PLATES

Samuel R. McCatcheon, Aloha, and Chester N. Winningstad, Portland, Oreg., assignors to Tektronix, Inc., Beaverton, Oreg., a corporation of Oregon

Filed June 12, 1961, Ser. No. 116,358
9 Claims. (Cl. 333—7)

The present invention relates to an electrical switch and more particularly to a switch for changing the electrical connections between a plurality of transmission lines having similar characteristic impedances by mechanical movement of the switch contacts.

The electrical switch of the present invention is particularly useful for changing the electrical connections between a plurality of coaxial cable transmission lines having substantially the same characteristic impedance, such as those used to transmit high frequency or pulse signals. Conventional electrical switches are not suitable in such an environment because they produce a discontinuity in the transmission lines which causes undesirable reflection of signal voltages back along the input transmission line.

In order to overcome the above problem it has previously been suggested to provide coaxial line switches which in effect operate by physically moving actual short sections of the coaxial cables from one position to another in order to provide continuous coaxial lines along alternate paths without reflection of signal voltages. However, this has not been an adequate solution to the problem because such switches are complicated, cumbersome and expensive.

The electrical switch of the present invention overcomes these disadvantages by providing broadly a simple mechanical switch in which only the central conductors of coaxial transmission lines are switched in order to change connections between the transmission lines while the outer conductors of such lines are fixedly connected to common conductors. More specifically, the switch includes a pair of spaced metal shield plates providing common connection for the outer conductors of the transmission lines, and a switch plate assembly for changing the connections between the inner conductors of such lines. The switch plate assembly includes a stationary stator plate and a movable rotor plate properly positioned between the shield plates so that the shield plates provide in effect an equivalent of the outer conductor of the coaxial cable transmission lines and the switch plate assembly provides an equivalent of the signal carrying inner conductor of the transmission lines. This simple, inexpensive structure provides a switch in the form of a short section of transmission line having substantially the characteristic impedance of the transmission lines connected thereto.

Therefore one object of the present invention is to provide an improved electrical switch which permits the changing of the electrical connections between a plurality of transmission lines without voltage reflections from said switch along said transmission lines.

Another object of the invention is to provide a simple electrical switch for changing the electrical connections between a plurality of transmission lines having similar characteristic impedances so that such switch has a structure which is in effect a transmission line section having substantially the same characteristic impedance as said transmission lines.

A further object of the present invention is to provide a switch, to change the electrical connections between a plurality of coaxial cable transmission lines having similar characteristic impedances, in which a switch plate assembly adapted to be connected to the signal carrying conductors of such lines and having a stationary stator mem-

ber and a moving rotor member is positioned in spaced relationship between a pair of spaced electrically conducting plates adapted to be connected to the outer conductors of such transmission lines so that the switch structure in effect forms a short section of transmission line having substantially the same characteristic impedance as the transmission lines connected thereto.

Additional objects and advantages of the present invention will become apparent upon referring to the following detailed description of a preferred embodiment of the present invention shown in the attached drawings of which:

FIG. 1 is a perspective view of an electrical switch made in accordance with the present invention;

FIG. 2 is a vertical section taken along the line 2—2 of FIG. 1 showing a portion of the switch and coaxial transmission line connections thereto; and

FIG. 3 is a section taken along the line 3—3 of FIG. 2 showing the switch plate and coaxial transmission lines connected thereto with connections to the outer conductors of such lines omitted.

An electrical switch made in accordance with the present invention is shown in FIG. 1 as including a circular metal support plate 10 which may have a conventional detent switch positioning means thereon including suitable mechanical stops. A suitable metal or nonmetallic shaft 12 is rotatably mounted in a hole through support plate 10 so that its rotation is controlled by the detent switch positioning means on such support plate 10. Two fastening bolts 14 extend through holes in the support plate 10. A metal spacer member 16 in the form of a cylindrical sleeve is mounted on each of these bolts 14 adjacent the support plate 10. A first shield plate 18 in the form of a circular, flat, metal plate having a pair of holes therein to accommodate the fastening bolts 14 and a clearance hole for the shaft 12, is mounted on such bolts against the spacer 16. A switch plate assembly 20 of insulating material provided with a pair of mounting holes for the fastening bolts 14 and a single hole for the shaft 12, is accurately spaced from the conducting plate 18 by a pair of insulating spacer sleeves 22 on the fastening bolts 14. A second metal shield plate 24 having a circular shape is mounted in a similar manner on fastening bolts 14 and spaced from switch plate 20 by insulating spacer sleeves 26 similar to sleeves 22. Circular shield plates 18 and 24 may have the same diameter and are provided with a concentric clearance hole through which the shaft 12 extends so that it is free to rotate without contacting the surface of such conductive plates. The switch assembly may be held on fastening bolts 14 and support plate 10 by means of a nut and lock washer combination 30 on the threaded end of such fastening bolts 14.

FIG. 2 shows coaxial cable transmission lines 32 connected to appropriate switch members including a pair of electrical connectors 34 extending between the grounded outer conductor 35 of each coaxial cable 32 and the common shield plates 18 and 24. Switch plate assembly 20 includes two concentric circular insulating members 36 and 38. The outer insulating member is a fixed annular stator plate 36 positioned on the fastening bolts 14 between insulating spacer members 22 and 26, while the inner insulating member is a circular rotor plate 38 having a hole therein fitting a flattened portion of the shaft 12 so as to be rotated by the shaft. The stator plate 36 has a plurality of pairs of fixed metal spring contacts 40 attached in spaced relationship around the stator plate so as to extend radially thereof. These fixed contacts 40 are each in the form of a spring member having an end which extends outwardly from the outer periphery of the stator plate 36 for connection to the central conductor 44 of a coaxial cable, such as the cables 32, by soldering or the like. The rotor plate 38 is provided with a plurality of

metal contact plates 46 in spaced insulated relationship which extend along the periphery of the rotor plate 38 and for a short distance over the inside edge of the stator plate 36 so that the outer surface of the contact plates 46 make mechanical contact with the spring ends of the fixed contacts 40 upon rotation of the shaft 12.

It should be noted that the switch plate assembly 20 is symmetrical in that a pair of fixed contacts 40 and a pair of movable contact plates 46 are attached by rivets 48 to such assembly with one element of the pair on each side of the stator plate 36 and rotor plate 38, respectively. One reason for this symmetrical arrangement is to minimize the electrical field which passes through the insulating stator plate 36 and insulating rotor plate 38 when signal voltages are transmitted through the switch so that dielectric losses therein are minimized. Each of the parallel shield plates 18 and 24 is placed substantially the same distance from the switch plate assembly 20 so that the switch is also symmetrical in this respect. The distances between the shield plates 18 and 24 and contacts 40 and 46 are such that the switch forms in effect a short section of a transmission line having a characteristic impedance substantially the same as that of the coaxial cable transmission lines 32. For example, when the coaxial cables 32 have a characteristic impedance of 50 ohms and the contacts 40 and 46 have a width of approximately $\frac{1}{8}$ inch, the space between such contacts and the conductive plates 18 and 24 should be approximately one-tenth of an inch. As a result, voltage reflections in the transmission lines 32 due to the line discontinuity formed by a switch are substantially eliminated by the switch of the present invention.

In FIG. 3 the coaxial cables 32 are shown as being connected to the center contact of two oppositely disposed groups of three contacts 40 on the stator plate 36. The rotor plate 38 may be rotated by the shaft 12 between two alternate positions in order to change the connections between the coaxial cables shown. In the position of the switch shown in FIG. 3 the input signal can enter the switch through one of the transmission lines 32, then pass through the connection formed by fixed contacts 40 and the movable contact plates 46 and by the connecting transmission line 52 to the other transmission line 32 which may be the output transmission line. Moving the rotor plate 38 counterclockwise to its alternate position will cause the signal to move through the connecting transmission line 54 so that it may be attenuated by an attenuator 56, or otherwise modified by any other suitable modifying means, before it is transmitted to the output transmission line. A greater number of switch contacts can be employed on the switch plate assembly for any switching purpose involving coaxial cable transmission lines or the like, usually with some loss of symmetry of the switch and some lack of continuity of the transmission line.

It should be understood that many variations in the details of the present invention may be made without departing from the spirit of the present invention. For example, the shape of the plates 10, 18, 20 and 24 may be other than circular, and the type of connectors 40 and 46 can be varied without departing from the scope of the present invention. Therefore, it is not intended to limit the present invention to the preferred embodiment described above but the scope of the invention should be determined solely by the following claims.

We claim:

1. A switch to change the electrical connections between a plurality of transmission lines having a pair of conductors and having similar characteristic impedances, comprising:

shield means including a pair of spaced shield plates to provide a common connection for one of the conductors of each of said transmission lines,

switch means including switch contacts positioned between the shield plates for interconnecting the other conductors of said transmission lines in a plurality

of different ways by movement of said switch means, and

support means to hold said shield plates and said switch contacts in proper spaced relationship to form a transmission line section having substantially the same characteristic impedance as said transmission lines.

2. A switch to change the electrical connections between a plurality of transmission lines each having a pair of conductors and having similar characteristic impedances, comprising:

shield means including a pair of spaced shield plates to provide a common connection for the ends of one of the conductors of each of said transmission lines, switch means including a plurality of fixed switch contacts positioned between said shield plates to provide a plurality of insulated connectors adapted to be connected to the ends of the other conductors in said transmission lines,

said switch means also including at least one movable switch contact positioned between said shield plates for interconnecting said fixed contacts in a plurality of different ways by movement of said switch means, and

support means to hold said shield plates, said fixed contacts and said movable contact in proper symmetrical spaced relationship to form a transmission line section having substantially the same characteristic impedance as said transmission lines.

3. A switch, used to change the electrical connections between a plurality of coaxial cable transmission lines having inner and outer conductors and having similar characteristic impedances, comprising:

shield means including a pair of spaced shield plates to provide a common connection for ends of the outer conductors in said transmission lines, switch means including a plurality of fixed switch contacts positioned between said shield plates to provide a plurality of spaced insulated connectors adapted to be connected to ends of the inner conductors in said transmission lines,

switch means also including at least one movable switch contact positioned between said shield plates for interconnecting said fixed contacts in a plurality of ways by movement of said movable contact, and

support means to hold said movable and fixed contacts approximately midway between said shield plates to form a transmission line section having substantially the same characteristic impedance as said coaxial cable transmission lines.

4. A switch, used to change the electrical connections between a plurality of transmission lines having similar characteristic impedances, comprising:

a pair of spaced shield plates of electrically conductive material adapted to provide common connections for the ends of shield conductors in said transmission lines,

a fixed switch plate having a plurality of insulated fixed switch contacts positioned between said pair of shield plates and adapted to be connected to the ends of signal conductors in said transmission lines, a rotatable switch plate having at least one movable contact positioned between said shield plates for interconnecting said fixed contacts in a plurality of ways by rotation of said rotatable switch plate, and

support means to hold said fixed and movable switch plates approximately midway between said shield plates to form a transmission line section having substantially the same characteristic impedance as said transmission lines.

5. A switch for changing the electrical connections between a plurality of electrical transmission lines having substantially equal characteristic impedances, comprising:

a pair of spaced shield plates of conducting material

adapted to be connected to the shield conductor in said transmission lines,
 a stator plate of insulator material mounted between said shield plates and having a hole therein,
 a rotor plate of insulator material mounted between said shield plates and inside said hole for rotation with respect to said stator plate,
 a plurality of movable metal contacts attached to the surface of said rotor plate in spaced, insulated relationship adjacent the periphery thereof for movement with respect to said rotor plate,
 a plurality of movable metal contacts attached to the surface of said rotor plate in spaced relationship and extending radially from said hole so that one end of each of said fixed contacts is positioned to engage said movable contacts on said rotor plate, and the other end of said fixed contacts is adapted to be connected to the signal carrying conductors in said transmission lines,
 and means to support said shield plates in proper spaced relationship with respect to said stator plate and said rotor plate to form a transmission line section having substantially the same characteristic impedance as said transmission lines.

6. A switch for changing the electrical connections between a plurality of electrical transmission lines having substantially the same characteristic impedance comprising:
 a pair of spaced shield plates of conductive material adapted to be connected to the shield conductors in said transmission lines,
 a stator plate of insulator material positioned between said shield plates and having a hole therein,
 a rotor plate of insulator material mounted between said shield plates and inside said hole for rotation with respect to said stator plate,
 a plurality of movable metal contacts attached in pairs to the opposite sides of said rotor plate with respect to said shield plates in spaced, insulated relationship adjacent the periphery thereof for movement with respect to said rotor plate,
 and a plurality of fixed metal contacts attached in pairs to the opposite sides of said stator plate with respect to said shield plates in spaced relationship and extending radially from said hole in said stator so that one end of each of said connectors is positioned adjacent the periphery of said hole adapted to engage said contacts on said rotor plate, and the other end of said connectors is positioned adjacent the outside edge of said stator plate adapted to be connected to the signal carrying conductors in said transmission lines, and
 means to support said stator plate and said rotor plate approximately midway between said shield plates to form a transmission line section having substantially the same characteristic impedance as said transmission lines.

7. A coaxial line switch, used to change the electrical connections between a plurality of transmission lines each having substantially the same characteristic impedance, comprising:
 a support member,
 a shaft rotatably mounted on said support member,
 a plurality of fastening elements fixedly mounted on said support member,
 a pair of spaced shield plates of electrically conductive material fixedly mounted on said fastening elements in spaced relationship and adapted to be connected to the grounded outer conductor of said transmission lines with the shield plate nearest said support member having a hole through which said shaft extends,
 a stator plate of insulator material having a hole therein fixedly mounted on said fastening elements and spaced between said pair of shield plates,
 a rotor plate of insulator material coaxially mounted

connected to one of the conductors to provide a common connection for one of the conductors of each of said transmission lines.

switch means including switch contacts positioned between the shield plates for interconnecting the other conductors of said transmission lines in a plurality of different ways by movement of said switch means, and

support means to hold said shield plate and said switch contacts in proper spaced relationship to form a transmission line section having substantially the

same characteristic impedance as said transmission lines.
